Genus and species: *Dahlia x hybrida*.

Variety denomination: 'KLEDH18119'.

BACKGROUND

The present invention comprises a new and distinct variety of *Dahlia*, botanically known as *Dahlia x hybrida*, and hereinafter referred to by the variety name 'KLEDH18119'. 'KLEDH18119' originated from an open pollination of the female *Dahlia* parent 'DH-2014-1288' (unpatented) in Stuttgart, Germany in 2014.

In 2015 a seedling was selected and named 'KLEDH18119'. In 2016, 'KLEDH18119' was first vegetatively propagated by vegetative stem cuttings. 'KLEDH18119' was found to reproduce true to type in successive generations of asexual propagation in Stuttgart, Germany and Latina, Italy via vegetative stem cuttings.

SUMMARY

The following are the most outstanding and distinguishing characteristics of 'KLEDH18119' when grown under normal horticultural practices in Stuttgart, Germany.

1. Red inflorescences; and
2. A compact, semi-upright habit.

DESCRIPTION OF THE PHOTOGRAPH

This new *Dahlia* plant is illustrated by the accompanying photograph of a plant of 'KLEDH18119' approximately 11 to 12 weeks old and grown in a greenhouse in Stuttgart,
